COMPRESSION-RELIEF MECHANISM.

1,101,935.

Specification of Letters Patent. Patented June 30, 1914.

Application filed April 11, 1912. Serial No. 690,098.

To all whom it may concern:

Be it known that we, HENRY W. JACOBS and WILLIAM J. LEIGHTY, citizens of the United States, and residents of Topeka, in the county of Shawnee and State of Kansas, have invented a certain new and useful Improvement in Compression-Relief Mechanism, of which the following is a description, reference being had to the accompanying drawings, which form a part of our specification.

Our invention relates to mechanism whereby compression in an internal combustion motor may be relieved, wholly or in part, as may be desired, or rather to suit the varying conditions which the motor may encounter.

The purpose of our invention is the provision of means whereby a multi-cylindered internal combustion motor may have all, a part, or none of the cylinders in operative condition through the manipulation or control of the exhaust valves, namely by holding a part or all of the exhaust valves of the cylinders open.

An object of our invention is the provision of a motor so constructed that a part of the motor in operation as well as the entire motor in operation, will be in good running balance.

A further object of the invention is the provision of an internal combustion motor having greater flexibility of power, as well as one resulting in greater economy of fuel, at the same time meeting the various conditions of service to which it may be subjected.

Another object of our invention is the provision of means whereby the different cylinders of the motor may be cooled, either all of the cylinders simultaneously or a part of them at any time; the means being adapted to control the exhaust valves of the respective cylinders so that a part or all of the exhaust valves may be held open, thus allowing cold air to be drawn into the cylinders by the reciprocating pistons and forced or blown out of the cylinders through the open exhaust valves.

The invention possesses other advantages which will be readily apparent from the following detailed description of the accompanying drawings, wherein:

Figure 1 is a plan view of an eight-cylindered air cooled internal combustion motor embodying our invention. Fig. 2 is a partial vertical sectional view taken on the

line A—B of Fig. 1, looking in the direction of the arrows, with the compression relief mechanism in operative position. Fig. 3 is a detail longitudinal sectional view of the cam-shaft engaging ends of the valve operating push rods.

In Fig. 1 of the drawings, we show the application of our invention to an eight-cylindered air cooled type of internal combustion motor, wherein a cam shaft 5 is shown extending lengthwise of the motor, and preferably at a point above the valve operating cam shaft. The shaft 5 has its bearings in a suitable number of brackets, 70 as at C, which may be secured to the cam shaft case for example, as more clearly shown in Fig. 2. The cam shaft 5 is provided with suitably arranged cams, corresponding in number with the number of cylinders of the motor; the different cams being placed on the cam shaft so as to be in alignment with the valve operating push rods of the different cylinders. For example, in the style of motor illustrated in Fig. 80 1, the cam shaft 5 is provided with eight cams; a cam 6 is arranged on cam shaft 5 at a point coincident with the valve operating push rods of cylinder D; a cam 7 is arranged coincident with the valve operating push rods of cylinder E; a cam 8 is coincident with the push rods of cylinder F; a cam 9 is arranged coincident with the push rods of cylinder G; a cam 10 coincident with the push rods of cylinder H; a cam 11 coincident with the push rods of cylinder I; a cam 12 coincident with the push rods of cylinder J; and a cam 13 is arranged coincident with the push rods of cylinder K.

In the exemplification of our invention, the mechanism is shown applied to a motor provided with concentric valves; that is, with the intake valve arranged within the exhaust valve and movable therewith; but the invention may be applied equally as well to a motor having separate intake and exhaust valves; the mechanism being adapted to control the position of the exhaust valve alone, and thereby give the necessary condition of compression relief in the different cylinders through the action of maintaining the exhaust valves of the selected cylinders in open position.

The details of construction and actual 110 operation of the mechanism can more readily be comprehended by referring to Fig. 2,

wherein the compression relief mechanism is shown in operative condition. The illustration shown in Fig. 2 is taken through cylinder E, in Fig. 1, so that the cam on cam shaft 5, shown in Fig. 2, is the cam 7; it being understood, of course, that the different cams and their relation to the push rods of the respective cylinders are identical, so that the description of one portion 10 of the mechanism will thoroughly describe the remainder of the mechanism and the operation thereof.

In the exemplification of our invention, we have disclosed the intake valve 14 and 15 exhaust valve 15 arranged concentrically; the valve being maintained in closed position by their respective springs 16 and 17. The valves in the construction shown are operated by the concentric push rods 18 and 19; the push rod 18 being arranged to operate the intake valve while the outer push rod 19 is adapted to operate the exhaust valve. With this construction, both valves move together when the exhaust valve is 25 opened; the intake valve, however, remaining on its seat formed by the exhaust valve, thus preventing an explosive charge entering the cylinder until the push rod 18 is operated independently of push rod 19, which 30 action is induced by the valve operating cam shaft 20, provided with suitable cams as at 21 and 22 for the intake and exhaust valve push rods respectively.

The lower ends of the push rods 18 and 35 19 are provided with roller carrying members or yokes 23 and 24; the carrier or yoke 24 being secured to push rod 19 and provided with a roller 25, which engages with the exhaust cam on cam shaft 20, while carrier or yoke 23, secured to the lower end of 40 push rod 18, is provided with a roller 26 which is adapted to engage with the intake operating cam on cam shaft 20. As shown in Fig. 3, carrier or yoke 23, is provided with 45 an extended portion or lug 23^a which fits onto a shoulder 24^a or into a slotway arranged in carrier 24, so that operation of carrier or yoke 24 will compel carrier or yoke 23, together with its push rod 18, to 50 move therewith.

Push rod 19 is provided with a shoulder or collar 27, see Figs. 2 and 3. Pivotedly mounted at 28, on a suitable bracket or extension of the cam shaft case of the motor, is a bell crank or fulcrumed lever 29, one end whereof may be bifurcated so as to extend to opposite sides of push rod 19 and beneath collar 27, as clearly shown in Fig. 3, while the other end of lever 29 may be provided 55 with a suitable antifriction surface or roller, adapted to engage with cam 7, see Fig. 2. The lever 29 is preferably held in inoperative position, when not acted on by its cam, through the action of a spring 30. The 60 spring will prevent the bell crank lever from

vibrating and thus avoid any undue noise in the motor.

When cam 7 engages the end of lever 29, the latter will be tilted on its pivotal point, thereby causing the opposite end of the lever to engage the collar 27 and push the exhaust valve rod 19 upward beyond the point where it can be acted on by the cam of the valve operating cam shaft 20. The upward movement of push rod 19 will force exhaust valve 15 open through the action of lever 31, thus relieving compression in the cylinder.

By reason of the connection between the carriers or yokes 23 and 24, secured to the lower ends of push rods 18 and 19 respectively, as previously described, push rod 18 will also be carried upward with push rod 19, and therefore maintain lever 32 in engagement with the stem of intake valve 14, thus preventing any undue vibration and noise. The action of bell crank lever 29, when depressed or oscillated by the cam 7, maintains both cam engaging rollers 25 and 26 beyond the operative orbit of the cams 21 and 22, thereby permitting cam shaft 20 to rotate freely without affecting the cam rollers 25 or 26 and their respective push rods.

The position or operation of cam 7 is 95 caused by the rotation of shaft 5, which is induced by a gear 33, secured on shaft 5, which gear meshes with a gear 34. Gear 33 is firmly secured or keyed to the shaft 5 while gear 34 is firmly secured or keyed to 100 the stub shaft 35, which is suitably mounted in bearings provided on the casing of the motor, as more clearly shown in Fig. 2. The outer or free end of shaft 35 is provided with any suitable operating mechanism, as 105 for example with a crank 36, see Fig. 1. The crank 36 is preferably provided with a flat spring 37, to one end of which is secured a pin 38, which may extend through an opening in the crank 36. Secured adjacent to 110 the crank 36, and preferably about the end of shaft 35, is a quadrant 39, which is provided with suitable holes or openings arranged in the quadrant at predetermined points, for example 90 degrees apart, so that 115 shaft 35 may be rotated to the desired extent and be locked or held in its rotated position. It is evident from the construction shown and described that shaft 35 may be rotated the desired degree and induce the desired 120 condition in the motor; for example, where the quadrant is provided with four holes arranged as previously stated, four conditions may be brought about through the operation of our improved mechanism, whereby 125 a portion of the exhaust valves may be maintained in open position when shaft 35 has been rotated to one point; a second portion or number of the exhaust valves maintained in open position when shaft 35 is 130

5 moved to another point indicated by the socket or hole in the quadrant; then, again, all of the exhaust valves will be maintained in open position when the shaft is revolved 10 so as to bring pin 38 to another or third hole or socket in the quadrant; or, none of the exhaust valves may be affected or held open when shaft 36 is rotated so as to bring pin 38 to another hole in the quadrant 39. 15 It will be understood, of course, that gears 33 and 34 are of equal diameter, so that one revolution of crank 36 will produce one revolution of the cam shaft 5.

It is understood, of course, as previously 20 stated, that cam shaft 5 is provided with a suitable number of cams so arranged that all of the push rods of the different cylinders may be simultaneously operated or only a portion of the push rods operated; and in 25 the illustration shown in Fig. 1, where an eight-cylindere motor is presented, the motor may be operated under the following conditions, to wit: First, when shaft 5 is moved a predetermined degree, the push rods of all the cylinders will be unaffected, 30 permitting them to remain where they will be operated by the respective cams of the valve controlling cam shaft 20; second, cam shaft 5 may be so rotated that the respective 35 bell crank levers 29 of the different cylinders will operate the proper push rods and relieve compression in cylinders D, E, F, and G, while cylinders H, I, J, and K remain operative; third, cam shaft 5 may be further rotated so that compression will be 40 relieved in all of the cylinders through the action of the different fulcrumed or bell crank levers on the respective push rods of the cylinders, whereby the rods will be held beyond the operative orbit of the cams on 45 valve controlling cam shaft 20; fourth, shaft 5 may be moved or rotated to another point or degree whereby the respective cams on shaft 5 and the corresponding bell crank levers will control or operate the push rods 50 of cylinders H, I, J, and K, and move them beyond the operative orbit of the cams on the valve controlling cam shaft 20, so that compression will be relieved in cylinders H, 55 I, J, and K, while at the same time permitting the push rods of cylinders D, E, F, and G to remain in operative position.

It will be understood, of course, that our improved mechanism can be applied to any 60 motor which can be divided into two parts and still maintain good running balance, as for example, on a four-cylindere double opposed motor, a six-cylindere V-type motor, an eight-cylindere V-type or vertical type motor, etc.; it being necessary to have the number of cams on shaft 5 and the number of bell crank levers correspond with the 65 number of cylinders with which the motor is provided.

70 By the use of our invention, the advan-

tage of having a high powered motor that can be operated with one-half the power, when the conditions imposed on the motor are light, may be obtained.

The advantage of our invention is apparent especially when applied to a motor-car; with the car running on a level road, and up to speed, it needs less than the maximum power, so that a portion of the motor can be cut out, thus saving the extra fuel necessary 75 to operate all the cylinders when the power required could be delivered by a portion or half the number of cylinders; while at the same time, cold air will be drawn into the inoperative cylinders, through their open 80 exhaust valves, resulting in an effectual cooling of the cylinders and their valves. It is evident, therefore, that the mechanism permits of a much wider range of power, and also greater economy; and also provides 85 an excellent method of cooling that part of the motor which is running light. Should the side or portion of the motor in operation show a tendency to heat, it can be readily alternated with the other or cooled side or 90 portion.

When occasion arises where the motor need not deliver power, the entire motor, or rather all of its cylinders can be put into inoperative condition, through the proper 95 relation of cam shaft 5, as above described; and by spinning crank shaft 36, and therefore cam shaft 5 also, all cylinders of the motor can be speedily scavenged and cooled, resulting in a very great advantage in the 100 starting and manipulation of the motor.

With our improved mechanism applied to an internal combustion motor, it will be seen that greater flexibility of power, as well as greater fuel economy may be had than 105 with other motors of the same designated power; while at the same time, providing a motor capable of meeting all conditions of service to which it may be put.

We have shown and described what we 110 believe to be the simplest and best form of our invention, but the same may be varied in certain details without, however, departing from the spirit of our invention. We do not wish, therefore, to be understood as limiting ourselves to the exact construction 115 shown and described, but

What we claim as our invention, and wish to secure by Letters Patent, is:—

1. Compression relief mechanism, consisting of means intermediate and independent of the valve operating cam shaft of an internal combustion motor and the valves of the cylinders of the motor, said means comprising a rotatable portion and an oscillating 120 portion in constant direct operative relation with each other, whereby the valves may be maintained inoperative.

2. Compression relief mechanism, consisting of rotatable means arranged intermedi- 125

130

ate of the valve operating cam shaft of an internal combustion motor and the exhaust valves of the cylinders of the motor, and mechanism for placing said means into operative relation with the exhaust valves, whereby predetermined degrees of rotation of said means will maintain the exhaust valves in an inoperative position.

3. Compression relief mechanism, comprising means arranged intermediate of the valve operating cam shaft of an internal combustion motor and the valves of the cylinders of the motor, whereby the valves of a selected number of cylinders will be held open in an inoperative position when said means is moved to a predetermined point, and the valves of all of the cylinders held open in an inoperative position when said means is moved beyond said point.

20 4. Compression relief mechanism, comprising means intermediate of the valve operating cam shaft of an internal combustion motor and the valves of the cylinders of the motor, whereby the valves of one-half of the motor may be held open in an inoperative position when said means is moved a predetermined degree and the valves of the other half held open in an inoperative position when said means is given a greater degree 25 of movement.

5. Compression relief mechanism, comprising means intermediate of the valve operating cam shaft of an internal combustion motor and the valves of the cylinders of the motor, whereby the valves of one portion of the motor and then the valves of the remaining portion or portions of the motor may be successively held open in an inoperative position and a running balance maintained.

40 6. Compression relief mechanism, comprising rotatable means adapted to have operative relation with the exhaust valves of the various cylinders of an internal combustion motor, said means being arranged to hold a predetermined number of exhaust valves open when rotated a predetermined degree and arranged to hold the exhaust valves of all of the cylinders open when given a greater degree of rotation.

50 7. Compression relief mechanism for an internal combustion motor, comprising a cam shaft adapted to have operative relation with the exhaust valves of the different cylinders of the motor, the cams of said shaft being so arranged that a portion of the exhaust valves of the motor will be held open in an inoperative position when said shaft has been rotated a predetermined extent and the exhaust valves of all of the cylinders held open in an inoperative position when said shaft is given a greater degree of rotation.

8. Compression relief mechanism for an internal combustion motor, comprising rotatably mounted means and a tiltably

mounted member intermediate of said means and the exhaust valve of each cylinder, said means being adapted to tilt a number of the members when rotated a predetermined degree whereby the exhaust valves of a predetermined number of cylinders are held in open position, while a further degree of rotation of said means will tilt the remaining number of tiltable members and maintain the exhaust valves of a second predetermined number of cylinders in open position.

9. Compression relief mechanism for an internal combustion motor, comprising rotatable means, and tiltably mounted mechanism intermediate of said means and the exhaust valve push rod of each cylinder, said means being arranged to tilt a portion of said mechanism when revolved a predetermined degree and thereby lift a predetermined number of push rods out of the operative orbit of the valve operating cam shaft of the motor, while further degree of rotation will tilt the remaining portion of said mechanism and lift the remaining number or all of the push rods out of the operative orbit of the valve operating cam shaft of the motor.

10. Compression relief mechanism for an internal combustion motor, comprising means adapted to be placed into operative relation with the exhaust valves of the cylinders when moved to predetermined points, whereby a portion or all of the exhaust valves will be maintained in open position without affecting the running balance of the motor.

11. In combination with the exhaust valve push rods of an internal combustion motor, rotatable means mounted adjacent to said rods, said means being arranged to lift the push rods of a predetermined number of the exhaust valves when moved through different degrees or arcs of a circle.

12. In combination with the exhaust valve push rods of an internal combustion motor, rotatable means, tiltable mechanism intermediate of the means and the rods, said means being arranged to tilt predetermined portions of the mechanism when moved through different degrees or arcs of a circle.

13. In combination with the exhaust valve push rods of an internal combustion motor, rotatable means mounted adjacent to said rods, said means being arranged to lift the push rods of a predetermined number of exhaust valves when moved through different degrees or arcs of a circle, and mechanism whereby said means may be operated and the position thereof maintained.

14. In combination with the exhaust valve push rods of an internal combustion motor, rotatable means, tiltable mechanism intermediate of said means and the rods, said means being arranged to tilt predetermined portions of the mechanism when moved

through different degrees or arcs of a circle, and mechanism whereby said means may be rotated and the position thereof maintained.

15. In a multi-cylndered motor, provided with a valve operating cam shaft, and exhaust valve operating push rods, the combination of a rotatably mounted shaft provided with prearranged cams coincident with said push rods, with means intermediate of said cams and the push rods whereby operative relation between said cams and the push rods is established when said shaft is given different degrees of rotation thereby maintaining the exhaust valves in open position.

16. In a multi-cylndered motor, provided with a valve operating cam shaft, and exhaust valve operating push rods, the combination of a rotatable shaft provided with prearranged cams at points coincident with said push rods, with tiltably mounted members intermediate of said cams and the push rods whereby operative relation between said cams and the push rods is established when said shaft is given different degrees of rotation and the exhaust valves maintained in open position.

17. In a multi-cylndered motor, provided with a valve operating cam shaft, and exhaust valve operating push rods, the combination of a rotatable shaft provided with prearranged cams at points coincident with said push rods, tiltably mounted members intermediate of said cams and push rods whereby operative relation between the cams and the push rods may be established, with mechanism whereby the shaft may be given different degrees of rotation and a portion or all of the push rods moved out of the operative orbit of the valve operating cam shaft.

18. In a multi-cylndered motor, provided with a valve operating cam shaft, and reciprocatingly mounted exhaust valve operating push rods, the combination of a rotatable shaft provided with prearranged cams at

points coincident with said push rods, pivotally mounted members intermediate of said cams and the push rods, with means for rotating said shaft whereby the members are tilted and the push rods reciprocated beyond the operative orbit of the valve operating cam shaft.

19. Compression relief mechanism for an internal combustion motor, comprising a rotatable shaft provided with prearranged cams, spring controlled tiltably mounted members arranged to be engaged by the respective cams on said shaft, and means whereby said shaft may be given the desired degree of rotation and maintained in position, in combination with the exhaust valve operating push rods with which the tiltably mounted members are adapted to engage.

20. An internal combustion engine comprising a plurality of pairs of explosive cylinders, the cylinders of each pair being set obliquely to each other, inlet and exhaust ports for each cylinder, inlet and exhaust valves for said ports, means to actuate said valves and to operate said engine, and mechanism to throw simultaneously by means of a single movement the valves of a plurality of cylinders into such position that said cylinders will be inoperative during the continuous operation of the engine.

21. An internal combustion engine, comprising a plurality of pairs of cylinders, the cylinders of each pair being set obliquely to each other, a driving shaft common to all of said cylinders, valve mechanism and ignition means common to all of said cylinders, and manually controlled means to render all the corresponding cylinders of the successive pairs on either side of the engine operative, while leaving the cylinders on the other side of the engine inoperative.
